UNITED STATES PATENT OFFICE.

RODMAN WANAMAKER, OF PARIS, FRANCE.

REPEATING WATCH.

SPECIFICATION forming part of Letters Patent No. 592,032, dated October 19, 1897.

Application filed January 28, 1897. Serial No. 621,007. (No model.)

To all whom it may concern:

Be it known that I, RODMAN WANAMAKER, merchant, a citizen of the United States, residing at Paris, France, have invented certain new and useful Improvements in Repeating Watches, of which the following is a specification.

The invention consists of an improved device for acting upon the sounding mechanism of repeating watches by depressing the crown of the watch and for locking and unlocking the repeating rack of the same. To that effect I fix the winding-up crown of the watch to a sleeve, having a square axial hole, sliding upon a square portion of the stem and engaging a rocking lever, provided within the watchcase and bearing upon a pin pivotally connected to a bell-crank lever pivoted on the face of the watch-plate. The said bell-crank lever has one of its arms projecting out of the circumference of the plate and pivotally connected to the one end of a curved rod, embracing part of the circumference of the plate, the said curved rod having its other end pivotally connected to the one end of a lever which is disposed in approximately radial position with respect to the watch-plate and which has its other end pivoted to the said plate, the purpose of the whole being to transmit to a suitable pin or projection of the usual rack of the repeating mechanism, which cannot be placed next the stem or crown, the pressure of the said stem or crown.

The invention further consists of an improved locking device of the repeating mechanism.

Now with a view of having the invention the better understood, I will proceed to describe the same with reference to the accompanying drawings, in which—

Figure 1 is a plan view of the repeating mechanism at rest, and Fig. 2 a similar view of the repeating mechanism in the position it assumes when the crown has just been depressed.

In the two figures similar letters of reference refer to the same parts.

A is the stem of the watch, having on its square portion a sliding sleeve A', to which is fixed the crown A². The lower end of the sleeve A' bears upon a rocking lever B', lodged in the watchcase-center B and piv-

oted to the same at b. The free end of said rocking lever B' bears upon a pin C, which engages a suitable radial or approximately 55 radial hole e' of the plate D and the inner end of which is pivotally connected to the arm E' of a bell-crank lever E' E², the fulcrum e of which is fixed to the plate D. The arm E² of the said bell-crank lever projects through the 60 border d of plate D and bears externally, pivotally fixed to it, the one end of a curved rod F embracing a portion of the circumference of plate D and having its other end pivotally connected to a lever G, which engages a suitable hole of the rim d of plate D and is connected to the face of said plate D by means of a pivot-screw g. The said screw g is at the same time the pivot of the usual rack J, acting upon a suitable pinion fixed to the axis h 70 of the repeating barrel placed on the opposite face of plate D.

The stroke of the repeating rack J is limited by means of a screw j, fixed to the plate D and playing in a curved slot j' of said rack J, 75 and the said rack J bears a screw or projection j², intended to be acted upon by the lever G. There is further provided a locking device K, formed of a lever having a spring-shaped portion k and being fixed to the plate D by means of a screw k'. The free end of the locking-lever K engages a suitable projection or nose l of the usual repeating rack L when the repeating mainspring has caused the said rack L to return to its rest position 80 shown in Fig. 1, the action of the said repeating mainspring being stronger than the strain of the spring M, which tends to throw the repeating rack L into the position shown in Fig. 2, in which its projection l' bears upon 90 the usual snail. (Not shown.) This throwing action of the spring M upon the rack L takes place as soon as the projection j², fixed to the rack J, engages the edge k² of the locking-lever K, as shown in Fig. 2, the said edge 95 k² being curved eccentrically with regard to the fulcrum g of the rack J, the repeating rack L being at the same time made independent of the mainspring-axis by any one of the well-known unlocking devices used in 100 repeating watches.

The described mechanism works in the following manner: The crown A² being depressed by the finger it causes the bell-crank

lever $E'E^2$ to be rocked from the position shown in Fig. 1 to that of Fig. 2. The said bell-crank lever $E'E^2$ being connected to the radial lever G by the curved rod F the latter 5 is also rocked and it withdraws thereby the screw j^2 , fixed to the rack J, which is rocked on its pivot g , and the mainspring of the sounding mechanism is wound up by means of the usual gearings, which do not belong 10 to the invention claimed. When the rack J arrives at the end of its stroke, the projection j^3 of the same lifts the locking-lever K out of engagement from the nose l of the repeating rack L, which is then thrown by the 15 spring M against the usual snail, limiting its stroke so as to sound the hours and quarters or minutes in the well-known manner.

Having thus fully described my invention, I claim—

- 20 1. In repeating watches, the combination of the crown A^2 , having a sleeve A' , engaged on a square portion of the stem A , with a rocking lever B' , acting upon a pin C, pivotally connected to the one arm of a bell-crank 25 lever $E'E^2$, the rocking movements of which are transmitted by means of an external

curved rod F to a lever G, pivoted to the pivot g , of the usual rack J, and bearing against a screw or projection j^2 , fixed to the said rack J, causing the said rack J to be rocked with 30 the said lever G, when the pin C is depressed by the action of the crown A^2 , substantially, as shown and described.

2. In repeating watches having a rack J, to act upon the main sounding-spring and a repeating rack L, to act upon the repeating hammers, the combination of a projection or nose l , of the repeating rack L with a locking-lever K engaging said projection or nose l , when the repeating mechanism is at rest, the 40 rack J bearing a screw or projection j^2 intended to act upon the eccentrically-curved edge k^2 of said locking-lever K, unlocking the same when the rack J is rocked, substantially as shown and described.

45 In testimony whereof I have signed my name to this specification in the presence of two subscribing witnesses.

RODMAN WANAMAKER.
